PAINT STIRRER AND BLENDER

Anne S. Shaw, Philadelphia, Pa.

Application August 30, 1949, Serial No. 113,061

3 Claims. (Cl. 259—107)

1

This invention relates to devices for stirring and blending viscous material, such as paints, paint enamels, lacquers and other similar coating substances.

The present invention embodies certain new and useful improvements over the stirrer and blender disclosed in Patent No. 1,926,655 granted to me under date of September 12, 1933.

The main object of the present invention is to provide a device for thoroughly stirring and mixing the liquid and solid ingredients and/or blending the various color pigments of paints and paint products, and which device by reason of the construction, combination and arrangement of its essential components, lends itself to ready application to the paint can or container either as a more or less permanent part of the lid thereof so that the mixing and blending may be accomplished while the can or container remains substantially hermetically sealed, or as a separate attachment for removable application to an open can or container to be supported in operative position from the rim or upper end of the container.

The device of this invention when installed when the container is filled and sealed, will in nowise interfere with the air tightness of the container or with the stacking thereof for storage and shipping, and also permits the container to remain hermetically sealed until it is desired to use the contents thereof.

The invention, together with the above and other objects thereof, will be best understood when the following detailed description is read with reference to the accompanying drawings in which are illustrated what are presently considered preferred embodiments of the invention, and wherein:

Figure 1 is a top plan view of a paint can having one form of my invention applied thereto;

Figure 2 is a vertical sectional view through the hermetically sealed can and further illustrating the application of the invention thereto with the parts shown in position occupied for storage and/or shipping purposes;

Figure 3 is a fragmentary vertical sectional-elevational view taken substantially on the line 3—3 of Figure 1;

Figure 4 is a fragmentary detail sectional-elevational view illustrating the application of the invention to a can equipped with the conventional lid and showing the crank and handle applied to the shaft of the paddle forming part of the invention; and

Figure 5 is a view somewhat similar to Figure 3

4 but showing the invention as applied to a friction top type of can and with the opening in the top for accommodating the handle shown in sealed condition.

5 In general the improved stirrer and blender comprises a bearing member adapted to be attached, in a manner hereinafter more fully explained, to a suitable support, such as for example the lid or top of a can or a plate adapted to rest on and be supported from the rim or upper end of the container, a shaft having its upper end journaled in the bearing bracket and a paddle mounted on the shaft to rotate therewith and characterized by oppositely disposed longitudinally twisted vertical blades and a horizontal blade bridging the vertical blades and secured to the latter at the lower ends thereof. Suitable handle means is also provided for the shaft of the stirrer or blender for rotating the latter to effect a mixing or blending of the contents of the can in which the stirrer or blender is placed.

Referring now in detail to Figures 1 to 3, inclusive, of the drawings, it will be seen that there is therein illustrated the usual form of container 10 or can for paint, varnish and similar coating surfaces. The can, therein designated by the reference numeral 10 is in this instance shown as provided with a closure or lid 11 having an upstanding peripheral rim from which extends a flange 12. The lid 11 telescopically fits within the upper end of the can 10 with the flange 12 seating against the flange 13 of the can, the lid and can thus co-acting to form a substantially airtight seal for the can. In applying the invention to this type of can and lid, therefore, the bearing bracket 14 of the stirrer or blender is welded or otherwise secured to the underside of the lid 11. The bracket 14, as shown, is substantially U-shaped with the legs thereof merging into lateral flanges or extensions that fit flatly against the underside of the lid 11 and secured thereto in the manner indicated.

40 Also in accordance with this invention the lid 11 of the can is constructed with a departure 45 from the conventional by having in the center thereof an opening 15 through which access is had to the shaft 16 of the stirrer or blender. Also in line with the opening 15 the lid 11 is provided at the underside thereof with a well 17, the peripheral wall of which is provided with an outstanding flange welded or otherwise secured to the lid 11 circumjacent the opening 15. In the bottom wall thereof the well 17 is provided with an opening that is in alignment with the open-

ing 15 in the lid 11 and with an opening provided in the bearing bracket 14.

Shaft 16 extends upwardly through the opening in the bracket 14 and into the well 17 through the opening in the bottom wall of the well, the upper end of the shaft terminating just short of the top of the well 17.

For purposes of transportation and storing, the space between the rim of the opening in the bottom wall of well 17 and the rotatable shaft 16 therein is hermetically sealed by solder as at 18, or other material softer than the surrounding and surrounded parts, so that this seal, while normally rigid will release the shaft 16 when sufficient torsional force is applied thereto. Also for purposes of transportation and storage, the opening 15 in the lid 11 is normally sealed by a disc 19 of solder or other suitable soft material which may be readily ruptured to permit access to the upper end of the shaft 16 when it is desired to manipulate the stirrer and blender.

Mounted on the shaft 16 for rotation therewith is a paddle comprising a cross member 20 that intermediate its ends is secured to the shaft 16, and at its opposite ends is provided with depending or vertical blades 21-21. The blades 21 at their lower ends are bridged by a horizontal blade 22. Preferably cross member 20 and blades 21 are formed from a single length of metal bent into a substantial U and the parts thereof forming the blades 21 longitudinally twisted as shown. The blade 22 is formed from a single length of metal and at its opposite ends is riveted or otherwise secured to the lower ends of the blades 21 as at 23. Also to provide a rigid structure, the lower end of shaft 16 is flattened and intermediate its ends the blade 22 is riveted or otherwise secured as at 24 to the flattened end of shaft 16.

The lower longitudinal portion of blade 22 is slit transversely intermediate its ends and the edge portions of the blade at opposite sides of the slit are angularly projected relative to the blade and in opposite directions with respect to one another as clearly shown in Figure 3.

A paddle having a blade assembly as just described and which characterizes this invention has been found to provide most efficient stirring action, the angular edges of blade 22 serving to lift the heavier material from the bottom of the can and the longitudinally twisted blades 21 cutting through the heavy or viscous solution all in a manner to effect a thorough mixing and blending with minimum physical effort on the part of the user and within a comparatively short period of time.

The upper end of the shaft 16 is squared or otherwise equipped as at 25 to accommodate an actuator for the stirrer. In the present instance the actuator consists of a lever or crank 26 provided at one end with a socket 27 complementing the end 25 of shaft 16 to receive said end of the shaft for effecting a positive engagement of the crank or lever 26 with the shaft. At the opposite end thereof the lever or crank 26 is provided with a threaded opening to receive the threaded end of a handle 28 as shown in Figure 4.

For storage and transportation purposes, the crank or lever 26 and handle 28 may be secured to the peripheral wall of the can 10 in any suitable manner, as for example by the use of solder 29, 30, as shown in Figure 1.

In Figure 5 the invention, as just described, is shown as applied to a can lid or top 31 of the well-known friction type. A comparison of Figures 2 and 5 will readily show that the invention

is applied to the friction top lid 31 of Figure 5 in substantially the identical manner in which it is applied to the conventional top 11 of Figure 2.

From the foregoing, it will be apparent that when it is desired to stir the contents of the can 10, the frangible disc 19 is readily broken, whereupon the socket 27 of crank 26 is passed through the opening 15 and engaged with the end 25 of shaft 16. Handle 28 is then readily secured in position on the lever 26 and when sufficient strength is applied to rotate shaft 16, the seal 18 will release the shaft 16 to permit rotation of the stirrer to agitate the contents of the can for mixing and/or blending purposes.

From the foregoing, it will also be apparent that in each form of the invention the stirrer may be moved up and down while being rotated, thus allowing the device to be used and operated in conjunction with cans of different depth; and also that, if desired, a selected end of lever 26 may be tapered or sharpened for insertion between the upper edge of the can and the flange 12 of top 11 or flange 35 of top 31, as the case may be, so that the crank 26 may be used for removing the lid or closure from the can.

From the foregoing it will be seen that a simple, effective and highly efficient stirring and blending device has been devised by virtue of which a rapid and efficient mixing of the contents of the can may be effected either while the can or container remains substantially hermetically sealed or while the can is in fully opened condition.

While the invention has been described in detail in its presently preferred embodiments, it will, of course, be understood that such has been done for purposes of illustration only and not by way of limitation, and therefore only such limitations are to be imposed thereon as may reasonably come within the scope of the appended claims.

What I claim is:

1. A paint stirrer and blender comprising means to support it in operative position on a container and embodying a bearing member and a well disposed above the bearing member and having a wall provided with an opening therein, a rotatable paddle including an actuating shaft having an upper end portion journaled in the bearing member and projecting into the well through the opening in the wall of the latter, manually operated means for actuating the shaft and means, comprising a solder joint, forming a normally rigid hermetic seal between the shaft and the surrounding wall of the well, adapted to release the shaft upon the application of torsional force thereto.

2. The combination with a container, a removable metallic closure therefor having an opening in the center thereof and a well below the opening provided with a bottom wall having an opening in alignment with the first-mentioned opening, a rotatable stirrer having an actuating shaft projecting into the well, a solder joint forming a normally rigid hermetic seal between the shaft and the surrounding wall of the well adapted to release the shaft upon application of torsional force thereto, and a frangible disc normally closing the opening in the closure and adapted to be ruptured to permit an operating handle to be passed through said opening for engagement with the actuating shaft for applying torsional force thereto to release and rotate the stirrer.

3. A paint stirrer and blender comprising in combination with a container, a removable closure for the container provided in the center there-

of with a well, a substantially U-shaped bracket secured to the underside of the closure and having the bight portion thereof in axial spaced alignment with the bottom of the well, the bottom portion of the well and the bight portion of the bearing having aligning openings, a stirring element having an actuating shaft extending through said openings and terminating at its upper end within the well, and a solder joint forming a normally rigid hermetic seal between the actuating shaft and the surrounding wall of the well adapted to release the actuating shaft upon application of torsional force thereto.

ANNE S. SHAW.
